Specification for Design.

Patented Dec. 2, 1919.

Application filed April 16, 1919. Serial No. 290,608. Term of patent 14 years.

To all whom it may concern:

Be it known that I, LAWRENCE R. BANDLER, a citizen of the United States, residing at New York, in the county of New York and State of New York, have invented a certain new, original, and ornamental Design for Rubber Sole-Pads for Boots and Shoes, of which the following is a specification, reference being had to the accompanying drawing, forming part thereof.

Figure 1 is a bottom plan view and Fig. 2 is a side elevation of a rubber sole-pad showing my new design.

I claim:

The ornamental design for a rubber sole-pad for boots and shoes, as shown.

In testimony whereof I affix my signature.

LAWRENCE R. BANDLER.
